CAN COVERING MACHINE

Ralph Benjamin Stevens, Yarmouth, Maine

Application August 7, 1931, Serial No. 555,681

20 Claims. (Cl. 113—14)

This invention relates to canning machinery and particularly to machines for placing the covers on filled cans which are later to be sealed, the invention including various improvements in such equipment and its operation as will be more fully set forth in the specification which follows.

While many features of my invention are adapted to general use and to cans of various types, I have selected for purposes of illustration equipment adapted to the packaging of flat or oblong cans such as are commonly used in the sardine industry, the covers of which are recessed or sunk below their edges. These covers or tops are usually oversized at the edge leaving a free lip area later to be rolled under as a seam. This, however, is to be taken as illustrative and is merely selected because these cans present various characteristic problems common to other types of cans, as well as certain problems peculiar to themselves.

My invention contemplates the handling of filled cans, the deposit and correct positioning of the cover thereon, and the transfer of the covered can without disturbing its cover for further operation, as for example, the closing of the cover seam. The proper positioning of these covers has always been a matter of difficulty. The matter of proper presentation of the filled can, the proper separation of the cover from a stack, the proper positioning of the cover and the probable maintenance of the cover or its position on the can are all matters of great importance where cans are to be tightly sealed and operations are to be carried on smoothly and rapidly.

My invention also contemplates certain correlation of parts whereby the covers are only dropped when a can is present, and also provides for the yielding of certain parts if and when a jam occurs as is often the case in the operation of such machinery.

In the accompanying drawings so much of the apparatus is shown as is immediately involved herein and as is required to illustrate the principles of my invention. Throughout the specification and drawings like reference numerals are employed to indicate corresponding parts, and in the drawings:

Fig. 1 is a plan view of a machine in accordance with my invention showing the separator blades extended into the cover stack.

Fig. 2 is a fragmentary plan view, showing the separator blades withdrawn to permit of the stack of covers to fall on the supports.

Fig. 3 a fragmentary partly sectioned elevation on the line 3—3, Fig. 1.

Fig. 4 is a section through the can runway show-

ing the cover-retaining rails bearing upon the cover on the filled can.

Fig. 5 is a view of the rear end portion of the apparatus.

Fig. 6 is a perspective view of the safety release of the feed slide mechanism.

Fig. 7 is a fragmentary section on line 12—12, Fig. 1, illustrating a modification of the cover plunger.

Fig. 8 shows a modification in the cam structure for operating the apparatus with the plunger mechanism shown in Fig. 7.

Fig. 9 shows in fragment the mechanism illustrated in Fig. 7, the plungers being shown in their lowermost positions.

Fig. 10 illustrates the can with cover travelling along the can carrier with the top of the cover engaging the cover retaining rails.

Fig. 11 illustrates in perspective the lever arrangement for slide feed of the apparatus.

Fig. 12 is a longitudinal partly sectioned view on the line 12—12, Fig. 1, the covers being shown in the stack, with one separated ready to be pushed into the cover dropping portion of the mechanism.

Fig. 13 is a fragmentary partly sectioned view through the cover dropping parts, the cover being shown fully seated on the can.

Figs. 14 and 15 show, respectively, the positions of the parts just previously and subsequently to the separating of the lower cover from the rest of the stack.

Fig. 16 is an end view of the eccentric cover support which permits of various adjustments of the distance between the separator blade and the surface on which the cover is supported.

Fig. 17 is a perspective showing the relation between the roll support for the cover and the separator blade.

Fig. 18 is a perspective of the separator blade, and Fig. 19 is a modified form of separator blade.

In the apparatus shown I have indicated a bed 1 traversed by a run-way 2 through which filled cans are moved by conveyor dogs 3. Above the way 2 is supported a frame 4 having a guide 5 through which a plunger 6 is reciprocated by a lever 7 pivoted at 8 in a post 9 supported on the frame 4. At its opposite end the lever 7 is provided with a roller 10 yieldingly pressed by the plunger spring 11 against a cam 12 on the main shaft 13.

The shaft 13 is mounted in bearings 14 and is driven as by a chain and sprocket 15. The shaft 13 also carries a beveled pinion 16 meshing with a similar pinion 17 on a vertical shaft 18. The shaft 18 has an arm 19 and roller 20 which en-

90

85

95

100

105

110

gages the lever 21 yieldingly held retracted by a spring 22. The lever 21 is linked as at 23 to the slide 24 the same being a pusher slide for advancing the lowermost cover from the stack to its position over the can.

The covers or can tops T are held in a stack frame 30 down which they tend to feed by gravity, the lowermost cover of the stack resting on an eccentric stop 31 when separated from the stack by the separators 32. These eccentric stops 31 may be rotated and locked in any desired adjustment by the nut 31¹. These separators are formed as blades having beveled ends 32¹ and projecting points 33 adapted to penetrate between the covers T and cause the separation of the lowermost one while at the same time supporting the rest of the stack. The separators 32 work in slide-ways 34 being moved by levers 35. The levers 35 are cross connected by links 37, 38, 39, the link 38 being fulcrumed at 38¹ and having its ends pivotally connected to 37 and 39 which in turn are pivoted to the levers 35. The levers are rocked on their pivots by a cross slide 40 having a roller 41 engaging a cam 42.

25 The cross slide 40 is continued across to the edge of the bed 1 where it is provided with a notch 40¹ disposed so as to be engageable by the hook end of the bar 43. The bar 43 is attached to a pivoted feeler 44 normally urged inwardly by a spring 45 so that it tends to enter the run-way 2 through which the filled cans pass. If no can is opposite the feeler 44 the bar 43 is drawn so that its hooked end engages the notch 40¹ as shown in Fig. 2, in which position the roller 41 is disengaged from the cam 42 and the separators thus allowed to fail of actuation so that no top is delivered to the stops 31 so as to be in alignment with the pusher slide 24.

In the operation of a machine of this sort where automatic operation is subjected to many factors of irregularity it is highly important to provide safety factors.

The slide lever 21 represents such a factor and for its relief in case of a jam I provide for its end pivot a special safety release. As shown in Fig. 6, this consists of a pair of jaws 21¹ pressed together by a spring 21² which yieldably engage the bearing post 21³. If there be an obstruction of the pusher slide 24 as by a jam in the feed, thereby causing an abnormal pressure to be exerted on the slide lever 21 by the roller 20 on the arm 19, instead of this increased pressure damaging the obstructed tops it will detach the spring pressed jaws 21¹ from the post 21³ and the feed of caps 55 stops.

In operation the filled cans C are fed to the run-way 2 in any desired way, being carried along by the conveyor dogs 3 which are advanced in any desired manner. When a can is properly positioned under the plunger 6 the slide 24 advances pushing a top T from the stops 31 across the shoulders of the guideway 31¹ to a position over the can. Here the edges of the cover or top T are yieldingly held by spring pressed end and side wings which center and guide it when pushed down by the plunger to proper position on the can C.

These wing guides comprise end and side members as follows. The outer or end guides 50 are pivoted in mounts 51 sustained by springs 52, their lower ends 53 aligning with the upper side of the cover when seated on the can body as seen in Fig. 13.

As the cover descends towards the can body from its elevated position, as shown in dot and

dash lines in Fig. 12, its ends engage the faces 54 of these wing guides 50 with a sliding contact, pressing them outwardly, but when the cover is firmly seated on the can (see Fig. 13) the wings swing inwardly over the cover and hold it in close engagement with the can temporarily or until in the advance of the can along the run way 2 the cover comes beneath the guide rails 2¹ which thereafter act to maintain this close relationship between cover and can body subsequent to their arrival at the closing machine.

The side guides 55 are pivoted at 56 in brackets 57 suspended from the frame plate 4 inside the line of travel of the conveyor dogs 3. They are slightly inclined as at 58 and spring pressed at 59 to grip the edges of the cover or top T when it is thrust between them by the slide 24.

The side guides 55 having the upper part of their inclined faces 58 in line with the edge of the cover or top T as advanced by the feed slide support the cover slightly above the end wing guides 50. This permits an endwise slip or adjustment of the cover T relative to the can C as well as its lateral positioning. As will be seen in the section of Fig. 9, the outer edge or rim of the top T is oversize and affords no guiding factor in centering the cover. The centering is dependent therefore on the engagement of the inwardly inclined edges of the cover depression with the outwardly inclined edge c of the can itself. Once interengaged these parts remain in correct position hence the gentle pressure of the rail 2¹ which maintains this engagement. The slide 24 having forced the rounded corners of the can top T between the side wings 55, the plunger 6 descends 110 causing the head 61 to engage with the top T, press it firmly on the can C.

In order to hold the can cover down during capping I may substitute for the guides 50 and 53 an additional pressing device on the plunger. The plunger shown in Figs. 7 and 9 differs slightly from the more simple type illustrated in the other figures. It is provided with plunger 71 on which is yieldingly mounted a head 72 and having a slight movement relative to the arms 73 which carry spring pressed edge pressers 74. These yield before the main plunger 72 contacts with the depressed portion of the cover T so that they are under a slight compression. When the main portion 72 of the plunger starts to rise to its position as indicated in dotted lines, Fig. 9, it is given a chance to clear the edges of the cover while these edges are firmly held in position by the edge pressers 74 which continue to exert a slight pressure while the can C is pushed forward and the cover T brought under the rail 2¹ which prevents its dislodgment as it is pushed along through the way 2.

I have indicated in Fig. 19 a modified form of separator 90 having lateral points 91 and usual central point 92. The lateral points are provided for certain covers which have a tendency unduly to stick together and thus need more effective separation.

The indicated modifications are illustrative of other variations of the structure shown which will be suggested to those familiar with this art.

What I therefore claim and desire to secure by Letters Patent is:—

1. In a can covering device, a bed having a transverse way for the filled cans a capping station on said way, means for moving the cans along said way, a cover stack at one side of the way, a pusher slide reciprocable under said stack, means for supporting the lowermost cover in

- alignment with said slide, separators for picking off the lowermost cover and for supporting the stack above it, pivoted spring pressed lateral guides disposed above the can capping station to 15 receive a cover from the pusher slide, a plunger for seating the cover on the can, means for yieldingly holding the cover on the can as the can is moved from under the plunger, and means for holding the covers on the cans during movement 10 along the way.
2. In a can covering device, a bed having a transverse way having an overhang along the edges thereof for the filled cans a capping station on said way, means for moving the cans 15 along said way, a cover stack at one side of the way, a pusher slide reciprocable under said stack, means for supporting the lowermost cover in alignment with said slide, separators for picking off the lowermost cover and for supporting the 20 stack above it, lateral guides disposed above the can capping station to receive a cover from the pusher slide, a plunger for seating the cover on the can, means for yieldingly holding the cover on the can as the can is moved under the overhang of the way.
3. In a can covering device, a bed having a transverse way for the filled cans a capping station on said way, means for moving the cans along said way, a cover stack at one side of the 30 way, a pusher slide reciprocable under said stack, means for supporting the lowermost cover in alignment with said slide, separators for picking off the lowermost cover and for supporting the stack above it, yieldable lateral guides disposed above the can capping station to receive a cover from the pusher slide, a plunger for seating the cover on the can, means for yieldingly holding the cover on the can as the can is moved from under the plunger, and means for holding the 35 covers on the cans during movement along the way.
4. In a can covering device, a bed having a transverse way for the filled cans a capping station on said way, means for moving the cans along said way, a cover stack at one side of the way, a pusher slide reciprocable under said stack, means for supporting the lowermost cover in alignment with said slide, separators for picking off the lowermost cover and for supporting the 40 stack above it, yieldable means disposed about the can capping station to receive a cover from the slide and support it over the can, and a plunger for seating the cover on the can.
5. In a can covering device, a bed having a transverse way for the filled cans a capping station on said way, means for moving the cans along said way, a cover stack at one side of the way, a pusher slide reciprocable under said stack, means for supporting the lowermost cover in alignment with said slide, separators for picking off the lowermost cover and for supporting the 45 stack above it, yieldable means disposed about the can capping station to receive a cover from the slide and support it over the can, a plunger for seating the cover on the can, and means for yieldingly holding the cover as the can is moved from under the plunger.
6. In a can covering device, a bed having a transverse way for the filled cans a capping station on said way, means for moving the cans along said way, a cover stack at one side of the way, a pusher slide reciprocable under said stack, means for supporting the lowermost cover in alignment with said slide, separators for picking off the lowermost cover and for supporting the 50 stack above it, yieldable means disposed about the can capping station to receive a cover from the slide and support it over the can, a plunger for seating the cover on the can, and means for yieldingly holding the cover as the can is moved from under the plunger.
7. In a can covering device, a bed having a transverse way for the filled cans, means for moving the cans along said way, a cover stack at one side of the way, a feed slide reciprocable under said stack, means for supporting the lowermost cover in alignment with said slide, means for separating the lowermost cover from said stack, pivoted feeler guides disposed above the can capping station to receive a cover from the slide, a plunger for seating the cover on the can, a lever for operating the cover feed slide, and means for yieldingly pivoting the cover feed slide 10
8. In a can covering device, a bed having a transverse way for the filled cans, means for moving the cans along said way, a cover stack at one side of the way, a cover feed slide reciprocable under said stack, means for supporting the lowermost cover in alignment with said slide, means for separating the lowermost cover from said stack, a pair of pivoted yielding feeler guides disposed above the can capping station to receive a cover from the slide, a second pair of feeler guides effective below the plane of said first mentioned guides, and a plunger for seating the cover on the can.
9. In a can covering device, a bed having a transverse way for the filled cans, means for moving the cans along said way, a cover stack at one side of the way, a cover feed slide reciprocable under said stack, means for supporting the lowermost cover in alignment with said slide, means for separating the lowermost cover from said stack, a pair of pivoted yielding feeler guides disposed above the can capping station to receive a cover from the slide, a second pair of feeler guides effective below the plane of said first mentioned guides, and a plunger for seating the cover on the can, and means for yieldingly holding the cover as the can is moved, and means for retaining the covers in position on the cans during movement along the way.
10. In a can covering device, a bed having a transverse way for the filled cans including a capping station on said way, means for moving the cans along said way, a cover stack at one side of the way, a slide reciprocable under said stack, rotatable eccentric stops for supporting the lowermost cover in alignment with said slide members each having a portion acting as a separator for picking off the lowermost cover and a portion for supporting the stack above it when said lowermost cover is separated and positioned on said eccentric stops.
11. In a can covering device, a bed having a transverse way for the filled cans including a capping station on said way, means for moving the cans along said way, a cover stack at one side of the way, a slide reciprocable under said stack, adjustable means for supporting the lowermost cover in alignment with said slide members each having a portion acting as a separator for picking off the lowermost cover and a portion for supporting the stack above it when said lowermost cover is separated and positioned on said adjustable means.
12. In a can covering device, a bed having a

- transverse way for the filled cans including a capping station on said way, means for moving the cans along said way, a cover stack at one side of the way, a slide reciprocable under said stack, means for supporting the lowermost cover in alignment with said slide, separators for picking off the lowermost cover, and for supporting the stack above it, a pair of pivoted spring pressed guides disposed above the can capping station to receive a cover from the slide, a second pair of guides disposed below the plane thereof, and a plunger for seating the cover on the can.
13. In a can covering device, a bed having a transverse way for the filled cans including a capping station on said way, means for moving the cans along said way, a cover stack at one side of the way, a slide reciprocable under said stack, means for supporting the lowermost cover in alignment with said slide, separators for picking off the lowermost cover, and for supporting the stack above it, a pair of pivoted spring pressed guides disposed above the can capping station to receive a cover from the slide, a second pair of guides disposed below the plane thereof, and a plunger for seating the cover on the can.
14. In a can covering machine, a bed having a way for filled cans, a capping station on said way, means for moving the cans along the way, a rail extending from the capping station along each side of the way and disposed to overlie the edges of the covers of the cans as moved from the station, and a detent on each side of the capping station and aligned with said rails and normally extending inwardly of the circumference of the caps but yieldable to permit the passage of the cap therewith as it is deposited on the can.
15. In a can covering machine, a bed having a way for filled cans, a capping station on said way, means for moving the cans along the way, a rail extending from the capping station along each side of the way and disposed to overlie the edges of the covers of the cans as moved from the station, and a guide pivoted at each side of the way and having a free lower edge normally aligned with the adjacent rail but yieldable to the edges of the cover as it is lodged on the can.
16. In a can covering machine, a bed having a transverse way, a capping station on said way, a vertically reciprocating plunger at said station including yielding edge pressers and a center contacting portion and having vertical movement relative to each other, and operating means adapted to raise the center contacting portion to clear the edge while the pressers are in contact therewith.
17. In a can covering machine, a bed having a transverse way, a capping station, a vertically reciprocating plunger at said station including yielding edge pressers and a center contacting portion and having vertical movement relative to each other, and operating means adapted to raise the center contacting portion to clear the edge while the pressers are in contact therewith, and a rail along each side of said way from said stations, and means for moving a covered can from the plunger to the rail prior to the release of the edge pressers.
18. In a can covering device, a cover stack, a pusher slide reciprocable under said stack, an eccentric stop rotatably mounted at the base of the stack for adjustment relative to the slide for supporting the lowermost cover in alignment with said slide, and separators for picking off the lowermost cover and for supporting the stack above it.
19. In a can covering device, a cover stack, a pusher slide reciprocable under said stack, an eccentric stop rotatably mounted at the base of the stack for adjustment relative to the slide for supporting the lowermost cover in alignment with said slide, and a pair of bevel end separator slides mounted for reciprocation relative to said stack.
20. In a can covering device, a cover stack, a pusher slide reciprocable under said stack, an eccentric stop rotatably mounted at the base of the stack for adjustment relative to the slide for supporting the lowermost cover in alignment with said slide, and a pair of bevel end separator slides mounted for reciprocation relative to said stack, and a replaceable separator point carried by the end of the separator slide and disposed centrally thereof.
